ATTORNEY.

UNITED STATES PATENT OFFICE.

ALEXANDER McDougall, of Duluth, Minnesota.

VESSEL SUPERSTRUCTURE.

1,380,110.

Specification of Letters Patent. Patented May 31, 1921.

Application filed October 18, 1919. Serial No. 331,606.

To all whom it may concern:

Be it known that I, ALEXANDER McDougall, a citizen of the United States, residing at Duluth, in the county of St. Louis and State of Minnesota, have invented certain new and useful Improvements in Vessel Superstructures, of which the following is a specification, reference being had therein to the accompanying drawing.

This invention relates to vessels and has special reference to a vessel adapted to the carrying of bulk oil or common freight as desired.

The principal object is to provide a vessel of this character which may be employed in either form of such service with as little inconvenience as possible, it being well known that tank vessels used in the oil business are not commonly employed in the carrying of any other form of freight.

Other objects and advantages of the peculiar means by which I accomplish such conveniently convertible vessel will appear in the further description of the invention.

In the accompanying drawing forming part of this application and in which like reference characters represent like parts:

Figure 1 is a side elevation of a flush deck self-propelled vessel embodying my invention.

Fig. 2 is a top plan view of same.

Fig. 3 is a transverse sectional view through the hatch coaming of the vessel.

Fig. 4 is a transverse sectional view of the hull of a vessel through one of the hatchways therein, illustrating two embodiments of the invention.

Fig. 5 is a similar view to Fig. 4 of a vessel having an upwardly extending trunk hatch coaming longitudinally the main deck thereof, and

Fig. 6 is an enlarged plan view of two of the hatchways embodying my invention.

In vessels designed for carrying oil a double walled bulkhead having a narrow space intermediate of the walls is formed at either end of the main cargo carrying hold and water is carried within such narrow spaces thus dividing the cargo hold

from the forward and after parts of the vessel which are employed for other purposes. These bulkheads are indicated at 1 and 2 in the drawings and which are no departure from those commonly used.

The holds of such vessels are also commonly divided into small compartments

made by numerous bulkheads, thwartships and fore and aft, so as to confine the oil in small spaces to keep it under control in the event of the ship laboring in rough weather.

Over each of such compartments is located an expansion tank or relatively smaller compartment to allow for the expansion of the oil and the carrying off of gasses arising from same due to its action within the compartments. On top of the expansion tanks are mounted pipes and valve connections for both filling and emptying the compartments as well as providing the necessary relief therefor, and suitable manholes are also provided within the tanks for access to the compartments.

In exclusive oil carrying boats these tanks are made fixtures to the deck or built up as parts of the vessel, such tank vessels having no provision for carrying other forms of cargo, such as hatches or the like and are confined strictly to the one form of cargo which naturally results in their being able to carry a cargo in but one direction only.

Now in my improved structure I provide the usual number of large hatches common to the ordinary freight carrying vessel and prefer to form such hatches with a low flat coaming indicated at 3 fixed to the deck 4 of the vessel with preferably a single plate 5, though two separate plates and expansion tanks may be used if preferred, at each hatch space. The upper face of the coaming 3 is inclined slightly away from the hatch and the hatch cover is securely bolted to the coaming as clearly indicated in Fig. 3 there being rubber or other forms of gasket employed intermediate of the cover and coaming to insure water and oil tight connection therewith.

By this form of hatch and coaming it is evident that the deck of the vessel can be made equally as strong and secure as if no hatches were formed therein and such hatch covers may be quickly removed by taking out of the bolts 6 and sliding or lifting them to a position intermediate of the hatches as illustrated in one instance in Fig. 6 of the drawings.

On top of the hatch plates 5 are permanently attached the rectangular shaped expansion tanks or compartments illustrated at 7, they corresponding in size and necessary equipment to those previously referred to as employed in the ordinary tank ship, the equipment usually consisting of a re-

lief valve and pipe indicated at 8, manholes indicated at 9, and other pipe connections such as for filling and emptying the tanks or for heating purposes, illustrated at 10.

5 Such vessel may be provided with a double bottom or not as desired and when constructed with a double bottom, the tank below can be used for oil cargo space, water ballast or for fuel oil for the vessel as preferred.

10 Some oil carrying vessels are equipped with a fixed upwardly extending trunk hatch coaming as illustrated at 11 in Fig. 5 and in such construction the hatches would be 15 formed transverse the top of the trunk and the hatch covers 5 carrying the expansion tanks 7 be moved fore and aft when desired in the same manner as when located directly upon the deck of the vessel.

20 Some compartments in the vessel may be fitted to carry liquid cargo for which no expansion tank is necessary or such compartments may not be entirely filled, in which event the manholes and pipe fittings 25 would be located directly upon the hatch plates 5 as indicated at 12 Figs. 1 and 4 and which may be inclosed within a small deck house illustrated at 13 securely fixed to the hatch plate. This house being a fixture upon the hatch cover would be moved 30 fore and aft with it when the latter is manipulated and such modification without the deck house might be especially desirable in the vessel having a continuous trunk hatch and in which the latter is used as expansion tanks for all of the compartments.

35 While the invention is illustrated as applied to a substantially rectangular shaped ship the same may be employed with equal 40 advantage to the common type of vessel.

45 From the foregoing it is evident that I have devised simple and comparatively inexpensive means whereby the usefulness of a vessel particularly designed for the carrying of bulk liquid cargo may be substan-

tially doubled and one which may be used in the transporting of other forms of freight with but little change in its equipment and the novel combination of hatch cover with the accompanying parts fixed thereto may 50 be slid or raised and lowered as required with but little more difficulty than the hatch covers without such equipment.

Having thus described my invention, what I claim as new and desire to secure by Letters 55 Patent is:

1. The combination with a navigable vessel having the cargo hold thereof divided into a plurality of individual cargo compartments and a plurality of hatch ways 60 communicating with said compartments, of removable hatch covers for said hatch ways, carrying fixed thereto expansion tanks substantially as and for the purpose described. 65

2. The combination with a vessel of the character described having a plurality of compartments therein for carrying bulk oil cargo, of hatchways through the upper deck of the vessel communicating with all of the 70 compartments, large flat covers for the hatchways and expansion tanks carried by the covers whereby the vessel may readily be used for carrying cargo other than bulk liquid. 75

3. A double purpose vessel of the character described comprising in combination a plurality of vertically separated cargo compartments, hatches in the upper deck of the vessel communicating with all of the 80 compartments, large flat covers for the hatches and expansion tanks for the compartments carried by the hatch covers.

In testimony whereof I hereunto affix my signature in the presence of two witnesses. 85

ALEXANDER McDougall.
